UNITED STATES PATENT OFFICE.

HARRY FRIEDMAN, OF LOS ANGELES, CALIFORNIA, ASSIGNOR TO ARCHITECTURAL IRON WORKS, OF LOS ANGELES, CALIFORNIA, A CORPORATION OF CALIFORNIA.

DESIGN FOR AN ELECTRIC-LIGHTING FIXTURE.

Application filed July 30, 1926. Serial No. 18,543. Term of patent 3½ years.

To all whom it may concern:

Be it known that I, HARRY FRIEDMAN, a citizen of Lithuania, (having declared his intention of becoming a citizen of the United States), residing at Los Angeles, in the county of Los Angeles, State of California, have invented a new, original, and ornamental Design for Electric-Lighting Fixtures, of which the following is a specification, reference being had to the accompanying drawing, forming a part thereof.

In the drawings, Fig. 1 is a front elevation illustrating in full lines a fixture showing my new design, the dotted lines indicating lamp bulbs; Fig. 2 is a side elevation of the same; and Fig. 3 is a bottom plan view of the fixture.

I claim:

The ornamental design for an electric lighting fixture as shown.

HARRY FRIEDMAN.
